UNITED STATES PATENT OFFICE.

CONRAD M. CONRADSON, OF MADISON, WISCONSIN.

PLANER-PLATEN GUIDEWAY AND BEARING.

1,367,802.

Specification of Letters Patent.

Patented Feb. 8, 1921.

Application filed October 2, 1919. Serial No. 328,011.

To all whom it may concern:

Be it known that I, CONRAD M. CONRADSON, a citizen of the United States, resident of Madison, county of Dane, State of Wisconsin, have invented certain new and useful Improvements in Planer-Platen Guideways and Bearings, of which the following is a specification.

The guideways for planer tables, particularly of the heavy duty type, are subjected to incessant friction under heavy pressure, directed especially in a downward direction. As ordinarily constructed in the cross section form of an inverted V, the downwardly slanting sides of the guide-ways induce the lubricating oil to run downward and escape from the bearing surfaces, thus destroying the oil film between the surfaces and resulting in excessive friction, increase in power necessary to drive the planer and inordinate wear on the guideways. Furthermore, the bearing surfaces of these guideways are necessarily, by the pyramidal form of their cross section, limited in area to prevent excessive height and weight of the platen and the general lack of sufficient bearing surface further increases the wear due to faulty lubrication.

The object of the invention is, therefore, to form the planer guideways with a large bearing area particularly effective for pressure in a downward direction and provide the guideways with a lateral bearing surface of a lesser area, while, at the same time, constructing the guideways in such a manner that the lubricating oil is conserved on the bearing surfaces to form a constant oil film between the sliding surfaces especially between those subjected to the greater vertical pressure.

A further object is to construct the planer frame and platen in a compact, rigid and cheaply machined form.

By these improvements I greatly increase the efficiency, economy and durability of the machine as heavier cuts may be taken with cutting tools, greater speeds of the reciprocating platen may be obtained and proportionately less power needed for a given amount of work to be accomplished.

My invention consists in certain constructions and combinations as set forth in the following detailed description and particularly pointed out in the claims.

In the accompanying drawings forming part of this specification,

Figure 1 is a perspective view of a planing machine having my invention applied thereto.

Fig. 2 is a vertical transverse section of the machine frame and platen, showing the preferable form of the guideways and also the gear for reciprocating the platen.

In the drawing, 3 represents the planer bed or main frame of the usual box type and having the side and upper housings 4, partly shown in Fig. 2. The top of the box-like frame structure is preferably closed the entire length of the machine by concave top-plate 5 cast integrally with the side and end walls of the frame and having ribs 6 running longitudinally from end to end of the main frame. These ribs are spaced a preferred distance from each other as shown, and their outer sides are accurately finished at an upwardly converging angle of approximately 15 degrees from the vertical to form the lateral guideways 7. At the points where the guide-ways 7 join the top plate 5, horizontal bearing surfaces 8 are machined on the plate and diverge outwardly and upwardly from the guideways at an angle of substantially ninety degrees from the ways or approximately 15 degrees from the horizontal to form the guide-ways 7. The bearing surfaces 8 are of much greater area than the guideways 7 and at the points of intersection I prefer to provide a slight undercut 9 for the purpose of proper lubrication. Longitudinal ribs 10 project from the outer extremity of the bearing surfaces to about the same height as the guideway ribs 6 and running parallel with said ribs form a trough for the reception of lubricating oil and prevent the lubricant from escaping from the bearing surfaces 7 and 8. An opening 11 is provided in the top plate 5 through which a driving bull gear 12, mounted loosely on a shaft 13, projects to reciprocate the planer table or platen by means of a rack 15.

The platen 14 is a hollow rectangular casting, consisting of the upper table plate 16 having the usual slots 17 for receiving the clamping bolts to hold the work to the table, the side walls 18 and 19 and the bottom plate 20, to which latter the rack 15 is secured. A central rib 21 is preferably arranged above the rack, joining the bottom plate 20 and table plate 16 together for the purpose of providing positive rigidity to the platen.

The bottom plate 20 is finished to exactly conform to the lateral guideways 7 and bearing surfaces 8 of the top plate 5 and proper clearance grooves 21 and 22 are provided for the ribs 6 and 10. The platen 14 rests on the bearing surfaces 8 and lateral movement of the platen is prevented by the guideways 7, slightly aided by the diverging angle of the bearing surfaces 8.

10 It will be noted that as the platen is reciprocated the maximum pressure and wear of the work is transferred to the broad area of the bearing surfaces 8, and that any occurring minimum lateral pressure is substantially absorbed by the smaller lateral guideways 7. It will also be noted that the peculiar rigidity of this construction renders the machine particularly adapted for heavy, accurate work and that the lubricant 15 will not tend to escape from the sliding surfaces, but on account of the slight inward and downward angle of the bearing surfaces 8 will tend to flow downward toward the guideways 7. The face of these being comparatively low will be constantly lubricated from the surplus oil collecting in the undercut grooves 9, from which oil will be spread to both the bearing and guiding surfaces.

It will be understood that the exact construction shown and described as to the degrees of angles and other details may be varied without departing from the principle and scope of the invention, and I do not, therefore, wish to confine myself strictly to the construction as shown.

I claim as my invention:

1. A machine bed having oppositely disposed correspondingly formed guides, the bottoms of said guides being slightly in-

clined inwardly and downwardly from the horizontal, the side surfaces of said guides being inclined inwardly and upwardly from the vertical, and a carriage having correspondingly shaped ribs to fit the surfaces of said guides.

2. A machine bed having oppositely disposed correspondingly formed guides, the bottoms of said guides being slightly inclined inwardly and downwardly from the horizontal, the side surfaces of said guides being inclined inwardly and upwardly from the vertical, and a carriage having correspondingly shaped ribs to fit the surfaces of said guides, the bottoms of said guides and ribs being of greater area than the side surfaces thereof.

3. A machine bed having oppositely disposed correspondingly formed guides and a carriage having ribs correspondingly shaped to fit said guides, said guides and ribs having lower surfaces inclined slightly to the horizontal and lateral surfaces intersecting said lower surfaces and inclined slightly to the vertical.

4. A machine bed having oppositely disposed, correspondingly formed guides and a carriage having ribs correspondingly shaped to fit said guides, said guides and ribs having lower surfaces inclined slightly to the horizontal and lateral surfaces intersecting said lower surfaces and inclined slightly to the vertical, and means for maintaining a constant lubricating film on said surfaces.

In witness whereof, I have hereunto set my hand this 19th day of September, 1919.

CONRAD M. CONRADSON.

Witness:

ALICE M. HAWLEY.
